(57) **CLAIM**

The ornamental design for a rechargeable xenon torch, as shown and described.

DESCRIPTION

FIG. 1 is a front view showing my new design.

FIG. 2 is a rear view thereof.

FIG. 3 is a side end view thereof.

FIG. 4 is other side view thereof.

FIG. 5 is a plan view thereof.

FIG. 6 is an underneath view thereof.

FIG. 7 is a front isometric view thereof.

FIG. 8 is a rear isometric view thereof.

FIG. 9 is a front isometric view with plug showing thereof; and,

FIG. 10 is a rear isometric view with plug showing thereof. The surface(s) or portion(s) of the article not shown in the drawing or described in the specification form(s) no part of the claimed design.
